UNITED STATES PATENT OFFICE.

EDWARD W. HILL, OF CHICAGO, ILLINOIS.

LOOSE-LEAF BINDER.

1,224,465.

Specification of Letters Patent.

Patented May 1, 1917.

Application filed February 12, 1916. Serial No. 77,837.

To all whom it may concern:

Be it known that I, EDWARD W. HILL, a citizen of the United States of America, residing at Chicago, Illinois, have invented a new and useful Loose-Leaf Binder, of which the following is a specification.

This invention relates to devices for binding loose leaves and papers in compact book form and one particular object of the invention is to provide a simple and practical device of this character in which the loose leaves or papers can be readily removed and replaced.

Another important object is to provide a binder in such form that all the leaves can be inserted or taken out together, instead of only a few at a time as in the binders at present on the market.

Another object is to provide for the locking of the binder to prevent unauthorized removal or insertion of the papers.

The foregoing and other objects I have accomplished by making the binder in the form of two separable opposed back members having leaf engaging means therebetween and detachably held together by securing means located adjacent opposite ends of said members but capable of being released from a single controlling point.

30 A considerable degree of adjustment of the back members to suit different thickness of the material therebetween is provided for by making the securing means in the form of rows of offset locking shoulders in one member arranged for engagement by locking shoulders on the other member.

Other features and details of construction will appear as the specification proceeds, attention being directed to the accompanying 40 drawings wherein I have illustrated my invention embodied in a practical and preferred form.

In these drawings:—

Figure 1 is a perspective view illustrating 45 the main parts of the binder in full lines and the covers and back in dotted lines, this view also illustrating, in dotted lines, the manner in which the binder is handled.

Fig. 2 is a similar view with the upper 50 member of the binder separated from the lower member.

Fig. 3 is a rear view of the binder mechanism with parts broken away.

Fig. 4 is a longitudinal sectional view of 55 the binder mechanism, the back cover being in position and shown in section.

Fig. 5 is a transverse sectional view taken substantially on the line 5—5 of Fig. 4, the upper part of the binder being indicated lifted off in dotted lines.

60

Fig. 6 is a detail perspective view of the push button and the locking device therefor.

The binder consists of two main parts 10 and 11 which I term the back members, and between which parts the leaves 12 are held, 65 suitable leaf-engaging means being provided, such means being illustrated in the form of telescoping posts 13 carried by the respective members.

The back members are angular in shape as 70 indicated, providing over-lapping back portions 10^a and 11^a and top and bottom portions 10^b and 11^b, forming opposed holding means for the leaves. These opposed back members are guided in sliding relation over 75 one another, in the present instance, by means of the telescopic leaf-binding posts.

The back members are secured together in adjusted relation by means of interengaging shoulders located near the opposite 80 ends of said members, said shoulders being provided in the construction illustrated by a series of openings or recesses in the inner back member arranged to be engaged by locking pins carried by the outer back mem- 85 ber.

The locking openings or recesses in the inner back member are designated 15 and are as shown in Fig. 2 arranged in a plurality of rows or columns with the recesses in one row 90 arranged in line with the recesses in the companion row. The locking pins are designated 16 and are shown carried by spring fingers 17. The ends of these locking pins are inclined as indicated at 18 so as to cause 95 them to yield as the two back members are forced together, the pins automatically interlocking with the appropriate shoulders when the two back members are brought together over the leaves.

The two backing members are unlocked from each other by mounting the locking pins on a supporting plate 20 on the back of the outermost back member, which can be retracted to withdraw the locking pins from 105 engagement with the locking shoulders. In the construction illustrated this locking plate is supported and guided on studs 21 projecting rearwardly from the back of the outer back member 11 and the retractive 110 movement of said plate is attained by the provision of retracting levers 22 pivoted at

their ends at 23 to outstanding lugs 24 on the ends of the locking plate and pivotally supported intermediate their ends at 26 on the supporting studs 21. Springs 26 engaged beneath the retracting levers and bearing against the locking plate serve normally to thrust said plate forward with the pins thereon interlocked with the shoulders on the inner back member.

For the purpose of operating said retracting means I employ in the present disclosure a push button 30 connected at 31 to the oppositely disposed ends of the two retracting levers, said push button working through an operating opening 32 in the back cover 33. This back 33 covers the back plates and the retracting mechanism and thus serves as a guard or shield for the same and at the same time it forms in effect the back of the binder so that it may be made more or less ornamental in appearance like the back of a book and affording also a rocker-like curved surface to diminish the jar as the relatively heavy book is opened in use. The effect of a book is further obtained by suitable front and back covers 34 and 35 connected with the two back members.

In the construction illustrated a relatively fine adjustment of the two back members is obtained by off-setting the holding pins of each locking device, substantially as indicated in Figs. 1, 2, and 3 so that when one of said pins engages with the locking recesses in one row the other holding pin will engage the blank space between the recesses in the companion row. The two locking pins of each pair are thus arranged to alternately engage with locking shoulders in the two rows of recesses. By adding other rows of locking shoulders and additional co-operating offset locking pins, still finer degrees of adjustment may be obtained. The supporting springs 17 which carry the locking pins are shown in the form of tongues cut from a single plate of spring metal. The alternating engagement of the offset locking shoulders is clearly illustrated in Fig. 3.

From the foregoing it will be clear that the binder can be opened by simply pressing on the push button 30, thus unlocking the two back members, and then separating said two members. The push button is preferably substantially centrally disposed and is conveniently operated by the thumb of one hand while the upper back member is conveniently lifted by the fingers of the other hand as indicated in dotted lines in Fig. 1. A thumb or finger hold may be provided in the upper member substantially as indicated at 37 so that said member may be readily grasped in the fingers of one hand. As soon as the pressure on the push button is released the springs 26 carry the locking plate forward and again project the locking pins

through the holes provided for them in the back plate 11^a into position to be engaged by the back plate of the other clamp member.

When the binder has been opened and the top lifted off any number of leaves can be slipped over the post 13 or other leaf holding devices and the binder is closed upon these additional leaves by simply replacing the upper member, the spring pressed holding pins yielding in this case as the upper member is applied and snapping into engagement with the proper locking shoulders on the inner back member.

As it is desirable at times to lock the binder to prevent unauthorized removal or insertion of leaves I provide locking means of simple form consisting of a stop which is interposed in back of the push button. This stop for the push button is indicated at 40 and is shown in the form of a cam disk carried by a stud 41 and having an upstanding shank portion 42 extending up into a bore 43 formed in the push button and bitted as indicated at 44 to be engaged by a suitable key 45.

The operation of this locking device will be readily understood, it being seen that when the locking cam is in the position indicated in Figs. 1 and 2, said cam will stand in line with a recess 47 in the underside of the tubular push button so that said push button may be operated to retract the securing means and that when said cam is turned part way to carry it from beneath said recess portion it will engage with the underside of the push button and prevent the same being operated to unlock the binder.

From the foregoing it will be apparent that by means of my invention the papers or leaves are firmly clamped at widely separated points but can instantly be released by the simple operation of a single conveniently located controlling device. When the top member of the binder is lifted off, all or as many sheets as desired may be inserted or removed as a single unit. Another advantage possessed by the invention is that the securing means for the two parts of the binder enables the setting of these two parts to practically any thickness of material within the range of adjustment of the binder.

What I claim is:

1. In a loose leaf binder, the combination of opposed back members, leaf engaging means between said members, interengaging locking shoulders on the respective back members adjacent opposite ends of the same for securing said back members firmly together and digitally operable means for simultaneously releasing both sets of said interengaging shoulders whereby said binder may be opened by hand without the use of a key.

2. In a loose leaf binder, the combination

of opposed back members, leaf engaging means between said members, interengaging locking shoulders on the respective back members adjacent opposite ends of the same 5 for securing said back members firmly together, digitally operable means for simultaneously releasing both sets of said interengaging shoulders whereby said binder may be opened by hand without the use of a key 10 and means for locking said digitally operable means inoperative to release the interengaging shoulders.

3. In a loose leaf binder, opposed back members, leaf engaging means between said 15 members, means for securing said members together in adjusted relation, digitally operable means for releasing said securing means to permit separation of the back members and means for locking said digitally 20 operable means inoperative to release the securing means.

4. In a loose leaf binder, opposed back members, leaf engaging means between said members, a plate movably mounted on one 25 of said members, coöperating locking shoulders on said plate and the other back member, means for normally holding the locking plate shifted into position with the coöperating locking shoulders in engagement, 30 means for shifting the locking shoulders in a direction to release the locking shoulders and means for locking said releasing means against releasing movement.

5. In a loose leaf binder, opposed back 35 members, leaf engaging means between said members, a locking plate mounted on one of said back members, coöperating locking shoulders on said plate and the other back member, a retracting lever operatively connected with said locking plate, a push button 40 for operating said retracting lever, and a locking member shiftable into the plane of movement of said push button.

6. In a loose leaf binder, opposed back 45 members, leaf engaging means between said members, a locking plate mounted on one of said back members, coöperating locking shoulders on said plate and the other back member, a retracting lever operatively connected with said locking plate, a tubular 50 push button for operating said retracting lever, and a locking member for said push button having an operating portion disposed in the plane of the tubular push button to 55 be thereby engaged and operated by a key inserted through said tubular push button.

7. In a loose leaf binder, opposed back 60 members, leaf engaging means between said members, a plate movably mounted on the back of one of said back members, locking shoulders carried by said plate adjacent the opposite ends thereof, locking shoulders on the other back member arranged to be engaged by the locking shoulders on the plate 65 carried by the first back member, means

for normally holding the locking plate shifted in position with the shoulders thereon engaged with the shoulders on the other back member and means for shifting said locking plate to simultaneously release both 70 sets of locking shoulders.

8. In a loose leaf binder, opposed back members, leaf engaging means between said members, a locking plate movably supported on the back of one of said back members, 75 spring pressed locking dogs carried by said plate and normally projecting beyond the face of the back member on which said plate is mounted, the other said back member having shoulders to be engaged by said spring pressed locking dogs, spring means normally holding the locking plate shifted with the locking dogs engaged with said locking shoulders and means for retracting 80 said locking plate.

9. In a loose leaf binder, opposed back members, leaf engaging means between said members, supporting studs on the back of the outermost back member, a plate guided on said studs, retracting levers pivoted on 90 said studs and connected with the opposite ends of said plate, a substantially centrally disposed actuating member connected with said retracting levers, locking shoulders carried by said retractable plate and shoulders 95 on the other back member to be engaged by said locking shoulders.

10. In a loose leaf binder, opposed back members, leaf engaging means between said members, supporting studs on the back of 100 the outermost back member, a plate guided on said studs, retracting levers pivoted on said studs and connected with the opposite ends of said plate, a substantially centrally disposed actuating member connected with 105 said retracting levers, locking shoulders carried by said retractable plate, shoulders on the other back member to be engaged by said locking shoulders and a locking member adapted to be interposed in the path of the 110 actuating member aforesaid to prevent retracting movement of the locking plate.

11. In a loose leaf binder, opposed back members, leaf engaging means between said members, supporting studs on the back of 115 the outermost back member, a plate guided on said studs, retracting levers pivoted on said studs and connected with the opposite ends of said plate, a substantially centrally disposed actuating member connected with 120 said retracting levers, locking shoulders carried by said retractable plate, shoulders on the other back member to be engaged by said locking shoulders and spring means engaged between the locking plate and the retracting 125 means aforesaid for normally thrusting the locking plate forward with the shoulders thereon engaged with the shoulders on the other back member.

12. In a loose leaf binder, opposed back 130

- members, leaf engaging means between said members, supporting studs on the back of the outermost back member, a locking plate guided on said studs, retracting levers pivoted on said studs and connected with opposite end portions of said locking plate, a tubular push button connected with the adjoining ends of said retracting levers, a locking member having an operating portion disposed in the plane of said tubular push button to be thereby engaged and operated by a key inserted through said tubular push button and interengaging locking shoulders on said locking plate and the other one of the back members.
13. In a loose leaf binder, opposed back members, leaf engaging means between said members, a retractable locking plate mounted on the back of the outermost back member, springs on the opposite ends of said locking plate, locking pins normally forced by said springs through the locking plate and through the back member on which said locking plate is mounted, locking shoulders on the other one of the back members arranged to be engaged by the locking pins and means for retracting the locking plate to thereby disengage the locking pins from the locking shoulders.
14. In a loose leaf binder, opposed back members, leaf engaging means between said back members, widely spaced apart supporting studs on the back of the outermost back member, a locking plate guided on said studs and having end portions extending beyond said studs, retracting levers pivoted on the outer end portions of said locking plate, pivoted intermediate their ends on the supporting studs and having their inner ends relatively closely approached, a push button connecting the approached inner ends of said retracting members, spring means acting on said retracting levers to thrust the locking plate forwardly against the back of the member on which it is mounted and interengaging locking shoulders carried by the locking plate and the other back member.
15. In a loose leaf binder, opposed back members, leaf engaging means between said back members, a hollow back shielding the back of the back members and provided with a substantially centrally located opening, a locking plate mounted on the back of the outermost back member, interengaging locking shoulders on said locking plate and the other back member, means for retracting said locking plate and an operating member for said retracting means working in the opening in the back of the binder aforesaid.
16. In a loose leaf binder, opposed back members, leaf engaging means between said back members, covers connected with said back members, a back shielding said back members and provided with a substantially centrally located opening, a locking plate mounted on the back of the outermost back member, locking shoulders on said locking plate adjacent the opposite ends thereof, locking shoulders on the other back member to be engaged by said first locking shoulders, retracting means for said locking plate and a substantially centrally disposed operating member for said retracting means operating in the opening in the back.
17. In a loose leaf binder, opposed back members, one of said members having two rows of transversely extending shoulders thereon with the shoulders in one row disposed in line with respect to the shoulders in the other row, offset locking shoulders carried by the other back member arranged for engagement with the locking shoulders on the first back member and leaf engaging members between said back members.
18. In a loose leaf binder, opposed back members, one of said members having two rows of recesses therein with the recesses in one row in line with respect to the recesses in the other row, two spring arms carried by the other back member, offset locking pins on said spring arms for engagement in the offset recesses of the other member and leaf engaging means between said back members.
19. In a loose leaf binder, inner and outer back members, said inner back member having two rows of locking recesses adjacent each end thereof, a pair of spring arms adjacent each end of the outer back member, locking pins carried by said spring arms for engagement with the locking recesses in the inner back member, means for retracting said locking pins from engagement with the locking recesses and leaf engaging means between the back members.
20. In a loose leaf binder, opposed back members, telescoping leaf holding posts carried by said members, a retractable locking plate mounted on the back of the outermost back member, locking pins carried by said locking plate, locking shoulders on the other back member for engagement by said locking pins, means for retracting said locking plate, a back housing said locking plate and retracting means provided with an opening therein and a push button working in the said opening in the back operatively connected with said retracting means.
21. In a loose leaf binder, back members, leaf engaging means between said members, two sets of interengaging locking shoulders on said back members, said locking shoulders being arranged in offset relation to thereby engage in alternation as said back members are brought together.
22. In a loose leaf binder, opposed back members, leaf engaging means between said back members, a hollow back shielding the back of the back members and provided with an opening therein, a locking plate

movably mounted on one of the back members, coöperating locking shoulders on said plate and the other back member, means for retracting the locking plate to disengage 5 the locking shoulders, and an operating member for the retracting means working in the opening aforesaid in the back of the binder.

23. In a loose leaf binder, back members, 10 leaf engaging means between said members,

locking shoulders arranged in parallel rows on one of said members, coöperating locking shoulders mounted on the other back member in line with the rows of locking shoulders on the first member and disposed to 15 engage locking shoulders in the respective rows in alternation as the back members are brought together and means for releasing the coöperating engaged locking shoulders.

EDWARD W. HILL.
